COIN SORTING APPARATUS

Wendelin P. Arnold, 835 6th St. S., Lethbridge,
Alberta, Canada
Filed Apr. 12, 1962, Ser. No. 186,983
1 Claim. (Cl. 133—3)

This invention relates generally to apparatus for sorting coins into their respective denominations according to diametral size.

A coin of one denomination usually differs in diametral size from a coin of small denomination, especially in the coinage of any one given country. Therefore, these coins may be distinguished and separated from each other according to their respective sizes. Devices that have been developed to achieve such separation comprises in general a flat plate having a plurality of circular apertures, one aperture being provided for each size of coin to be sorted. The plate is usually inclined to the horizontal and is provided with a guide means so that the coins when placed on an upper portion of the plate will pass along the surface thereof, in contact with the guide means, by gravity. The circular apertures abut the guide means and are arranged in the order of increasing size in the direction of travel of the coins. Thus, when the coins pass along the plate, the smallest coins drop through the first and smallest aperture, the next larger coins will pass over the first aperture to drop through the second aperture, and so on. A receptacle is usually provided beneath each aperture for collecting the coins passed therethrough.

Such sorting devices, however, are limited in their use because of the slow speed at which the coins must pass along the plate to achieve smooth and accurate separation. When a coin reaches its aperture, it does not fall straight through the aperture but follows a trajectory determined by its weight and speed. Also, the circular aperture has a diameter only slightly larger than that of the coin so that it will not affect the next larger coins passing thereover to a larger aperture. Accordingly, each coin must travel very slowly in order that its trajectory is almost negligible, otherwise the coin may strike the trailing end of the aperture and rebound or may even over-shoot it. High coin speeds, therefore, cause coins to interrupt or jam the flow of coins by rebounding into the path of the following coins. High speeds also cause "misfires," that is, coins over-shooting their respective apertures to pass through a larger aperture into the wrong receptacle.

Attempts have been made to overcome this disadvantage of speed limitation but have resulted only in adding another. These attempts have been to provide additional guide means for each of the circular apertures to ensure that each coin drops only into its respective aperture while permitting larger coins to pass thereover. In certain cases, abutments have been employed on the trailing end of each aperture so that a coin is brought to a full stop before it drops through its aperture. However, the only significant results are that the sorting plates have become very complicated with numerous projections which may deflect a coin from its path and thereby disrupt the flow of coin.

It is, therefore, an object of the present invention to provide a sorting apparatus for coins or the like which is of greatly simplified construction compared with prior sorting devices and capable of sorting coins or the like at much higher speeds than hitherto known.

The essence of the invention is the use in a sorting apparatus for coins of a plate having elongated apertures and a surface devoid of obstructions to impede the passage of coins thereover. Guide means are pro-

2

vided to guide the coins to the apertures which are arranged successively in the order of increasing size in the direction of travel of the coins. Each aperture is located adjacent the guide means but with its adjacent edge spaced therefrom a distance less than the radius of the coin to be passed therethrough. The remote edge of each aperture is spaced from the guide means a distance just greater than the diameter of the coin but less than the diameter of the next larger coin. The elongation of each aperture is defined by a leading and a trailing end spaced apart in the direction of travel of the coins a sufficient distance to prevent the coin from striking the trailing end as it passes through the aperture.

Coin sorting devices according to the present invention have proven to be extremely successful in the high speed sorting of large amounts of unseparated coinage such as the receipts of newspaper publishing companies, bottling companies, recreational centers, etc. Not only does the simplicity of these devices result in such greatly increased sorting speeds but also in very high sorting accuracies required for the subsequent counting and wrapping of the sorted coins.

Two embodiments of the present invention are described below with reference to the attached drawings in which:

FIGURE 1 is a perspective view of a first embodiment of a coin sorter according to this invention;

FIGURE 2 is a fragmentary cross-sectional view taken on line 2—2 of FIGURE 1;

FIGURE 3 is a plan view of the coin-sorting plate and its mounting means, and

FIGURE 4 is a perspective view of a second embodiment of a coin sorter according to this invention.

The embodiment shown in FIGURE 1 comprises a casing designated generally at 10 having a base plate 11, end walls 12 and 13 and a rear wall 14. Supported at the top ends of the end walls 12 and 13 and the rear wall 14 is a hopper indicated generally at 15 having a sloping floor 16 inclined downwardly away from a flat portion 17 towards a steeply inclined end wall 18. The sides of the hopper are defined by steeply inclined side walls 19 and 20. The sloping floor 16 has a chute 21 extending beyond the end wall 18 and is spaced from the bottom edge of the end wall 18 to form a slot 22 as shown in FIGURE 2. The chute 21 of the sloping floor 16 has upwardly extending flanges 23 along both sides thereof which are extensions of the side walls 19 and 20.

Disposed on the base 11 of the casing 10 is a frame 24 having upwardly extending end walls 25 and 26 which support at their upper ends a longitudinally and transversely inclined plate 27, hereinafter referred to as slide 27. The upper end of the slide 27 has side flanges 28 and 29 which extend along the remaining portion of the slide 27 as guide flanges 30 and 31, respectively. The upper portion of the plate 27 between the flanges 28 and 29 has mounted thereon an upwardly curving plate 32 located beneath the free end of the chute 21 of the hopper 15. The curved plate 32 and the flanges 28 and 29 form a coin receiving portion of the slide 27. Positioned between the flanges 28 and 29 at the upper edges thereof and spaced from the curved plate 32 is a curved deflector 33.

The downwardly sloping surface 34 of the slide 27 is substantially flat and has arranged therealong adjacent the guide flange 30 a succession of apertures 35 to 39 of successively larger sizes from aperture 35 to aperture 39. Between the end walls 25 and 26 of the frame 24 is a sloping shelf 40 having partitions 41 defining a plurality of compartments. A plurality of receptacles 42 to 46 are removably positioned within these compartments beneath the apertures 35 to 39, respectively.

Before the apertures 35 to 39 are described in greater detail, the operation of the sorting device will be described briefly with reference to FIGURE 2. The coins are first placed on the flat portion 17 of the hopper 15 and are then pushed by hand onto the sloping floor 16 when they slide by gravity through the slot 22 and down the chute 21. The flanges 23 insure that the coins slide to the free end of the chute 21 from where they fall onto the curved plate 32 of the slide 27.

The slot 22 prevents too many coins falling onto the plate 32 at one time, by limiting the passage of the coins therethrough. The deflector 33 between the side flanges 28 and 29 ensures that the coins lie flat as they slide by gravity down the curved plate 32 onto the surface 34. Because of the longitudinal and transverse inclination of the slide 27 the coins slide on their flat surfaces along the surface 34 in contact with the guide flange 30. Each coin will slide or roll down surface 34 until it reaches the aperture through which it is intended to pass. The coin then falls through that aperture into the receptacle underneath where all the coins of the same denomination are collected.

As shown in FIGURES 1, 2 and 3 five apertures are provided, one each for ten cent, one cent, five cent, twenty-five cent and fifty cent pieces in that order. Any coin larger than the fifty cent piece, such as a silver dollar, will travel all the way down the slide 27 and drop over the end thereof into a suitable container (not shown in this first embodiment) which may be provided for this purpose. With reference to FIGURES 2 and 3, it will be noted that each aperture is in the shape of a trapezoid and is spaced from the guide flange 30 against which the coins are in contact when they travel down the slide 27. The apertures are successively larger in size in the direction of passage of the coins down the slide 27. As exemplified by aperture 39, each aperture is defined by an edge 47 adjacent to the guide flange 30, a remote edge 48, a leading end 49 and a trailing end 50. The adjacent edge 47 is spaced from the guide flange 30 by a web 51 which is wide enough to support the near edge of a coin passing thereover but is not as wide as the radius of the coin intended to pass through the aperture. The remote edge 48 of each aperture is spaced from the guide rail 30 a distance just greater than the diameter of the coin which is to pass through the aperture but less than the diameter of the next larger coin.

A coin that will pass through the aperture 39, in this case a fifty cent piece, will slide over the other apertures until it reaches aperture 39. The coin then begins to fall downwardly about its edge which is supported on the web 51. The coin, however, does not drop directly down into its receptacle 46, but follows a slight trajectory. Because of this trajectory the trailing end 50 is spaced from the leading end 49 a distance sufficient to permit the leading edge of the coin to drop below the surface 34 without striking the trailing end 50. The leading end 49 is provided with a downwardly sloping lip 52 which guides the coin smoothly into its trajectory and prevents the coin tipping sharply and obstructing the flow of the following coins. Each of the other apertures 35 to 38 is similarly adapted to allow passage therethrough of the coins of the respective diametral sizes and denominations. It should be noted, however, that the apertures do not need to have the exact configuration shown in the preferred embodiment described above, they may assume other similar shapes so long as they fulfill the general requirements noted. For example, the apertures could be rectangular and need not have the lip 52 on the leading end 49 thereof.

FIGURE 4 illustrates a second embodiment of the invention which is similar to the first embodiment but is adapted for handling greater numbers of coins. In

this embodiment, a double slide 53 is provided having surfaces 54 and 55 inclined to the horizontal in the same longitudinal manner but inclined in opposite directions to each other in the transverse direction and joined together at their uppermost longitudinal edges. The surfaces 54 and 55 have guide flanges 56 and 57 disposed along their lowermost longitudinal edges, respectively, and have corresponding rows of apertures adjacent to these flanges as described with reference to the first embodiment. A common receptacle is located below each of the corresponding pairs of apertures to receive the coins passed therethrough. A hopper 58 is arranged similarly to the hopper 15 of the embodiment of FIGURE 1 except that it is provided with a central partition 59 to divide the flow of coins from the flat surface 60 onto the two surfaces 54 and 55 of the double slide 53. In this particular embodiment only four different sized apertures are provided in each surface 54 and 55 with the largest coins to be sorted sliding down the length of these surfaces and dropping over the ends thereof into a receptacle suitably positioned thereunder. A double deflector 61 is located between the upper ends of the flanges 56 and 57 to deflect the coins on each part of the slide 53 in a manner similar to that of the deflector 33 in the first embodiment.

The apparatus according to this invention has been described throughout as a coin sorting apparatus. It is not to be limited to such however, as it would find use in any application requiring the sorting of disk-like objects similar to coins according to their diametral sizes.

What I claim as my invention is:

Apparatus for the high speed sorting of coins according to diametral size comprising a hopper having a flat portion onto which coins to be sorted may be dumped, a downwardly inclined tapered portion onto which coins may be pushed by hand from said flat portion, a wall facing said downwardly inclined tapered portion and terminating above the latter to define a coin passage therebetween, side walls extending upwardly from said downwardly inclined tapered portion to confine the coins thereon, a concave plate arranged in front of said coin passage but spaced therefrom such that coins passing through said passage will strike said plate to eliminate riding of one coin or another and will have their direction of movement reversed, a flat plate along which said coins travel from said concave plate, said flat plate being downwardly inclined longitudinally and transversely and having a succession of variously-sized apertures and guide means along the lower longitudinal edge of said flat plate for guiding said coins to the apertures, said apertures being successively larger in the direction of travel of said coins, each of said apertures having an edge adjacent said guide means and spaced therefrom a distance less than the radius of a coin to be passed through the aperture, an edge remote from said guide means and spaced therefrom a distance greater than the diameter of said coin but less than the diameter of the next larger coin, and leading and trailing ends sufficiently spaced apart in the direction of travel of said coins so that said coin in passing through the aperture will not strike said trailing end.
